[57] CLAIM

The ornamental design for a watercraft, as shown and described.

DESCRIPTION

FIG. 1 is an enlarged front perspective view of a watercraft showing my new design;
FIG. 2 is a rear perspective view thereof;
FIG. 3 is a front elevational view thereof;
FIG. 4 is a rear elevational view thereof;
FIG. 5 is a top plan view thereof;
FIG. 6 is a bottom plan view thereof; and
FIG. 7 is a side elevational view thereof, the opposite side elevational view being a mirror image of that shown.
